CANDLE SOCKET

Rudolf Popp, Valparaiso, Ind., assignor to McGill Manufacturing Company, Valparaiso, Ind., a corporation of Indiana

Application August 20, 1932, Serial No. 629,636

9 Claims. (Cl. 173—354)

My invention relates in general to electrical switch mechanisms and more in particular to an improved switch mechanism in combination with a candle type of socket.

5 The principal object of the invention is the provision of a simplified construction in a device of the character set forth.

Another object is the provision of improved means for assembling the switch and socket 10 parts.

Another object is the provision of improved means for attaching the switch element to the socket.

15 A further object is the provision of improved means for attaching and supporting the candle shell.

A still further object is the provision of an improved switch and candle socket assembly.

Other objects and features of the invention 20 will be apparent from a consideration of the following detailed description, taken with the accompanying drawing, wherein:

Fig. 1 is an elevational view of the complete assembly;

25 Fig. 2 is an elevational view taken from the same angle, but with the candle shell shown in section;

Fig. 3 is an elevational view similar to Fig. 2, but looking at Fig. 2 from the right hand side 30 thereof;

Fig. 4 is an enlarged longitudinal sectional view taken along the line 4—4 of Fig. 1;

Fig. 5 is a sectional view taken along the line 5—5 of Fig. 4;

35 Fig. 6 is a transverse sectional view taken on the line 6—6 of Fig. 4, looking upwardly;

Fig. 7 is a transverse sectional view looking downwardly, taken on the line 7—7 of Fig. 4;

Fig. 8 is a perspective view of one of the portions of the assembly including the center lamp contact;

Fig. 9 is a perspective view of an assembly member which functions to secure the shell contact to the switch assembly;

45 Fig. 10 is a plan view as seen on the line 10—10 of Fig. 4, looking in the direction of the arrows; and

Fig. 11 is an elevational view of the contact bridging member.

50 Referring now to the drawing, the switch includes a pair of frame members 11 and 12 formed of insulating material, such as fibre, a phenolic condensation product, or the like. These frame members function not only to support the switch elements proper but also to support the

mounting nipple, center and shell contacts of the socket, and the usual candle shell.

Considering now first the stationary switch contacts, one contact 13, formed of spring material, is attached to a frame spacer and assembly member 14. This spacer member is relatively square and it has a pair of center projections extending through apertures or slots in the frame members, which projections may be up-ended or flattened, if desired, to secure the frame 5 members thereto. The contact 13 has a relatively squared portion 13a, this squared portion having tabs or extensions 13b, four in number, clinched over the spacer 14. These tabs abut the extensions on the spacer and also when the 10 assembly is made these tabs lie between the spacer and frame members (Fig. 7) whereby the contact member is held firmly in position. The contact member is arched as shown to facilitate 15 its operation as a contact member.

The second stationary contact member 16 has a squared portion 16a provided with a plurality of tabs 16b, which clinch over a spacer 17 (Fig. 8) on opposite sides of the extensions 17a. This construction is substantially the same as in the 20 case of the contact member 13, the spacer extension 17a projecting through square holes in the frame members 11 and 12, and adapted to be flattened or up-ended. The spacer 17, however, has a center contact extension 18 carrying the center lamp contact 19. This center contact extension 18 projects through an aperture in the screw shell 21 and also through an aperture in an insulating disc 22, disposed in the 25 bottom of the shell in such a way that the center 30 contact 19 is held in its proper position.

For assembling the shell 21 to the frame members 11 and 12, I provide a combination spacer and assembling member 23 (Fig. 9). This member has a pair of spacing portions 24 and 26, provided with extensions 24a and 26a respectively. These extensions project through openings in the frame member and are also adapted to be clinched over or up-ended to hold the frame 35 members together. The member 23 also has extensions 27 which project through apertures in the base of the shell and also through the insulating disc 22, where they are clinched over to attach the shell to the frame members.

By the arrangement so far described, it is clear 40 that I have a direct metal connection between the center lamp contact 19 and the stationary contact 16. The member 23 in electrical contact with the shell is apertured and threaded to receive a conductor or lead attaching screw 28. 45 50 55

The spacer member 14 carrying the contact 13 is also apertured and threaded to receive a screw 29. Through these two connections the switch contacts, including the lamp, may be connected 5 into a main circuit which supplies power to the lamp.

The moving contact member is a substantially star-shaped bridging contact 31 carried on a toothed wheel 32 having an integral ratchet wheel 10 33 and projecting axis members 34 journaled in the frame members 11 and 12. The composite member comprising the members 32 and 33 is 15 formed of insulating material, preferably a suitable molding compound. The portion 32 has teeth, the space between the teeth being alternately shallow and deep, and arms 31a of the bridging contact 31 have portions 31b formed at an angle to the arms and overlying the teeth. The stationary contacts 13 and 16, formed with 20 the arcuate ends, engage the space between the teeth and, when disposed in the shallow spaces between the teeth, engage the overlying portions 31b, thus bridging the two stationary contacts.

The movable contact is operated through an 25 integral ratchet wheel 33 by means of a substantially U-shaped operating member 36. This member has two arms, one of which is bent over at 37 to form an operating pawl and the other of which is disposed flat along the teeth of the 30 ratchet wheel to balance the part bearing the pawl. The member 36 has secured thereto a bar 38, which extends through the base of a U-shaped spring housing 39. This U-shaped spring 35 housing is apertured to receive an annular projection on an assembly nipple 41, this projection being riveted over to connect the assembly nipple to the spring housing. A spring 42 has one end engaging against the member 36 and the opposite end engaging against the spring housing around 40 the outside of the adjacent portion of the assembly nipple, this spring tending to force the member 36 upwardly when in the position shown in Fig. 4. This bar 39 has a universal joint connection to a switch operating lever 43 of a well known 45 type, this switch operating lever being adapted to be pulled or pressed at any angle to pull the bar 38 downwardly and operate the movable switch contact.

The U-shaped spring housing 39 also furnishes 50 as a spacer and assembly member for the frame members 11 and 12. It is provided with projections 39a which extend through the frame members and may be clinched over or up-ended to serve as rivets.

55 A tube or shell 44 of insulating material extends over the entire assembly and is shaped and formed up to represent a candle in a well known manner. I provide improved means, however, for securing this candle shell to the assembly. 60 The frame members have a pair of projections 46 near the bottom thereof, one on each frame member. The candle shell has a pair of bayonet shaped slots 47 and 48, one slot extending up a considerable distance and the other slot being 65 relatively short but in alignment with an aperture 49. These slots are spaced apart from each other a distance equal to the distance between the projections 46. In assembling the candle shell, it is slid down over the assembly with the 70 slots in alignment with the projections 46 and serving as guides. One projection 46 rides into the opening 49, the candle shell springing slightly to allow it to enter. In the meantime, the slot 47 continues to act as a guide so that the projection 75 will finally become lodged in the aperture 49.

The slot 47 has a narrowed portion 47a, so that when the projection 46 passes such narrowed portion, it will be held in the end of the slot. The two projections, therefore, operate as detents to prevent rotational movement of the candle shell 5 and also to prevent it from being withdrawn readily from the assembly.

Among the features of the invention is the fact that substantially every member employed in the assembly functions as a spacer and may function 10 as a riveting means for securing the frame members together. It is not necessary to employ all of the projections through the frame member for this purpose, however, as the candle shell in itself serves to support the frame members to some 15 extent. It should be noted, also, that in each instance a member for connecting the shell and center contacts to the stationary switch contacts also serves as spacers. The member 23 secures 20 the shell to the frame members and also functions to establish electrical contact to the shell through the screw connection 28. The stationary contacts 13 and 16 are identical, except that they are secured to different types of mounting members. Looking at Fig. 8, it will be seen that 25 the stationary contact 16 is apertured to correspond with the contact 13 through which the screw 29 passes. This aperture in the contact 16 is, of course, of no importance, but illustrates that the two stationary contact members are 30 identical, thus facilitating manufacture and assembly.

The frame members are provided with marginal recesses 51 through which the lead wires are 35 adapted to pass. It will be noted that these marginal recesses are in alignment with the projections 46, thus making it possible to cut the frame members from sheet material at some considerable saving. It should also be noted that the two 40 frame members are identical, which eliminates one part carried in stock, and facilitates and simplifies manufacture and assembly.

One of the features of my invention is the simplicity with which it may be assembled. As a first 45 step, the disc 22 is placed in the screw shell 35 and the assembly and spacer may be assembled with the screw shell by inserting the extensions 27 through the apertures provided in the screw shell and disc and clamping these extensions over. One of the frame members is then laid 50 in a jig, all of the spacers and switch elements placed in the jig and assembled to the one frame member, the second frame member placed upon the top of the previously partially completed assembly and the projections extending through 55 the frame members upended to hold the members in assembled relation. The last step, of course, is to assemble the candle socket, which is accomplished in the manner previously described.

Although I have disclosed my invention in detail to permit those skilled in the art to practice the same, I do not restrict myself to the particular form shown and described, but the invention is limited only by the scope of the appended claims.

65 What I claim as new and desire to protect by Letters Patent of the United States is:

1. In a candle socket, a pair of substantially flat frame members parallel to each other, said frame members having a pair of projections, electrical switch mechanism disposed between the frame members and supported thereby, a screw shell secured to the frame members, and a candle shell in the form of a tubular insulating cylinder 70 surrounding said frame members and screw shell, 75

said candle shell having a pair of end slots, one slot being relatively long and the other relatively short, an aperture being provided in line with the short slot, one frame projection disposed in the 5 long slot to guide the candle shell and the other to engage in said aperture.

2. In a candle socket, a pair of flat frame members formed of insulating material, a plurality of formed integral sheet-metal spacer and assembly members disposed between the frame members and having extensions projecting through the frame members to hold them substantially parallel to each other, a screw shell abutting the frame members, one of said spacer and assembly 10 members having lugs extending through the base of the screw shell and bent over to thereby fasten the frame members to the screw shell, another one of said spacer and assembly members having a projection extending through an aperture in 15 the screw shell and disposed to constitute a center lamp contact, said two spacers forming electrical terminals of the shell and center contacts respectively.

3. A candle socket as defined in claim 2, including a pair of stationary contacts, one attached to the same spacer member which carries the center lamp contact and the other attached to another one of the spacer and assembly members, and an adjustable bridging contact disposed between the 20 frame members for forming a connection between the stationary contacts.

4. In a candle socket, a pair of flat substantially rectangular frame members formed of insulating material, four spacer and assembly 25 members, one disposed at each corner of the rectangular frame members for spacing said members, each of said spacer and assembly members having an extension projecting through the frame members for holding the frame members 30 together and substantially parallel to each other, a pair of stationary contacts, each one secured to a spacer and assembly members at diagonally opposite corners and having brush ends extending toward the middle of the frame members, a rotatable bridging contact device including a 35 step-by-step rotatable contact wheel disposed between the frame members substantially midway between the corners thereof engaged by the brush ends, means carried at one end of the frame members for operating said bridging contact device to open and close the circuit between the 40 stationary contacts, and a screw shell supported at the opposite end of the frame members.

5. A candle socket as defined in claim 4, where- 45 in said stationary contacts are provided with a plurality of projections bent over the spacing

members to which they are attached so as to lie on either side of the extensions of such spacing members and between the spacing members and the frame members.

6. A candle socket as defined in claim 4, where- 5 in one of the spacing members has a plurality of integral projections extending through apertures in the shell and clinched over to attach the screw shell to the frame members.

7. A candle socket as defined in claim 4, where- 10 in one of the spacing members has a plurality of integral projections extending through apertures in the screw shell and clinched over to attach the shell to the frame members, one of the 15 spacer and assembly members carrying the stationary contact having an extension disposed through an aperture in the shell and shaped to provide a center lamp contact, and means carried by the spacer and assembly member which supports the shell and by the spacer and assembly member carrying the second stationary contact for connecting the socket to a source of 20 power.

8. In a candle socket a pair of elongated flat 25 rectangular frame members formed of sheet insulating material, said members being identical and each having two marginal recesses along one edge on adjacently disposed edges, a lug extending from the opposite edge of each member disposed in alignment with a recess in the opposite edge, said members being punched from sheet material whereby each lug is formed from the material taken out of the recess of the adjacently punched member, spacer members for holding the frame members in alignment, terminals mounted on the frame members one adjacent each pair of opposite recesses whereby said recesses permit passing of conductors from the terminals to the outside of the frame, and a tubular candle shell placed over the frame 30 member held by said lugs.

9. In a candle socket, a pair of frame members comprising flat pieces of insulating material, a plurality of sheet metal spacer and assembly members disposed between the frame members, one of said spacer and assembly members disposed at one end of the frame members with a portion flush with the upper edges thereof, a shell socket mounted above said spacer and in contact with the flush portion, an insulating plate 45 resting within the shell socket upon the bottom thereof, integral lugs on said spacer and assembly member extending through said shell socket and insulating plate to rigidly secure the socket to said assembly and frame members. 50

RUDOLF POPP. 55
